UNITED STATES PATENT OFFICE

167,698

TELEVISION TUBE BODY

Francis M. Lambert, Narberth, Pa., assignor to
Heintz Manufacturing Company, Philadelphia,
Pa., a corporation of Pennsylvania

Application July 28, 1950, Serial No. 11,452

Term of patent 14 years

(Cl. D26—8)

To all whom it may concern:

Be it known that I Francis M. Lambert, a citizen of the United States of America and a resident of Narberth, in the county of Montgomery and State of Pennsylvania, have invented a new, original, and ornamental Design for Television Tube Body, of which the following is a specification, reference being had to the accompanying drawings, forming a part thereof.

Fig. 1 is a perspective view of a television tube body, showing my new design;

Fig. 2 is a side elevational view;

Fig. 3 is a rear elevational view;

Fig. 4 is a top plan view; and

Fig. 5 is a front elevational view thereof.

I claim:

The ornamental design for a television tube body, as shown.

FRANCIS M. LAMBERT.
